Inventor:
John Henry Pickard

By his Attorney: Malco Gunn

UNITED STATES PATENT OFFICE.

JOHN HENRY PICKARD, OF ROCHDALE, ENGLAND.

ADJUSTABLE WRENCH.

Application filed April 5, 1921. Serial No. 458,698.

To all whom it may concern:

Be it known that I, JOHN HENRY PICKARD, a subject of the King of Great Britain and Ireland, residing at Rochdale, in the county 5 of Lancaster, England, have invented new and useful Improvements in Adjustable Wrenches (for which I have filed application in Great Britain October 9th, 1917, under No. 14,579/17, Patent No. 112,603), of 10 which the following is a specification.

This invention relates to wrenches and refers in particular to wrenches of the type in which one edge of one of the limbs or parts is provided with a plurality of notches, 15 sockets, or gaps, adapted to receive a hinge pin or pivot, and with any of which, said pin may be engaged by moving one limb or part longitudinally in relation to the other, and the object of the present invention is to 20 provide a wrench of the kind referred to of improved construction.

According to this invention the edge of the shank of the slidable jaw is provided with open recesses to receive a pivot pin 25 of non-circular formation in cross section, the arrangement being such that when said shank is turned at a certain angle relatively to the stationary jaw shank one of the recesses in the former can be passed into engagement with or disengaged from the pivot pin, but when said jaws and shanks are in the operative position the conformation of the recesses and the pivot pin is such that the latter cannot be drawn out of the 30 recesses, a spring preferably being provided tending to turn the relatively moving shank into the operative position. Instead of moving the jaws and jaw shanks relatively to each in order to adjust the 35 spanner the pivot pin may be mounted so as to be capable of a part rotary movement in order to turn the same into position in which the recess in the respective shank is free to engage or leave the same.

40 The invention will be more particularly described by the aid of the accompanying drawings in which:

Fig. 1 is a part sectional view of an adjustable wrench constructed according to the 45 invention.

Fig. 2 is a corresponding view showing the two parts turned into position in which they can be disengaged.

50 Fig. 3 is a sectional plan view on the line 3, 3, Fig. 1.

Fig. 4 is a view corresponding to Fig. 3,

but showing a pivot pin capable of being rotated.

Referring to the drawings, the main portion *a* of the wrench is formed of sheet metal 60 which is shaped and bent up so that serrated ears *b* are formed at one end, said ears being connected by a distance piece and constituting one of the jaws.

The body portion is trough shaped, as 65 seen in Fig. 3, and receives the sliding member, which has a head portion *d*, the under-side of which is serrated at *e* to coact with the before mentioned serrated ears *b*. Said serrated face is formed at an acute angle 70 to the extension or handle *c* and the serrations are continued for a short distance down the extension. The latter is formed with any desired number of depressions or recesses *f* to receive the pivot pin *g* which is 75 riveted in position. The shape of the latter in cross-section is about two thirds of a circle and the recesses *f* are of similar conformation so that the distance between the flat side *g'* of the pin *g* and the opposite rounded side 80 of said pin is narrower than the width of the pin at right angles to the first measurement and equal to the width of the front opening *f'* in the recesses *f*. In order that the greatest angle of movement may be obtained without any tendency of the sliding member to leave the pivot pin, the front opening *f'* is formed at an angle, the under-side of the recesses *f* extending further round 85 the pivot pin than the top side as clearly 90 seen in the drawings.

When the handles *a* and *c* are turned into the position shown in Fig. 2, it will be seen that the narrow way of the pivot pin is in line with the restricted opening *f'* of the 95 recess *f*, consequently the two parts can be readily separated and a different recess engaged for adjustment purposes. A spring *h* may be secured to the back part of the handle *a* as shown in Fig. 1 which tends to turn 100 the handle *c* into the position in which the recesses engage the pin, and when in this position, while the two parts can be turned about one another they cannot be drawn apart owing to the width of the opening *f'* 105 being less than that of the pivot pin except across the flat *g'*.

Instead of the pivot *g* being fixed to the handle *a* it may be rotatably mounted as shown in Fig. 4. In this case the pin *g'* is 110 of the same sectional shape as the pivot pin *g* but one end is provided with a milled head

g^3 while the other end is screw-threaded to screw into the opposite side of the main portion a , a spring washer k being interposed beneath the head g^3 to retain the pin in the adjusted position. The arrangement is such that the pin g^2 is normally retained with the flat in the position shown in Fig. 1, but said pin can readily be turned into position where the arm c 10 can be drawn clear without the necessity of moving said arm c into the position shown in Fig. 2. If desired the pin g^2 may be riveted over to prevent the entire withdrawal of the same. By these means the 15 wrench can be adjusted to suit objects of different sizes in a simple and expeditious manner, without loose parts.

What I claim is:—

1. In combination, in an adjustable wrench, two main parts each having a roughened part forming a jaw, and each also having a handle part, and one of said main parts being hollow and the other solid and extending through the hollow part, a pivot 20 pin secured to the said hollow part and having a flat portion on one side, said solid main part having a series of recesses in one edge with anyone of which the pin may engage, the entrance to each recess being 25 less than the widest diameter of the said

pivot pin but slightly greater than the diameter of the pin at the flat portion, the pivot pin being arranged so that only when the main parts of the wrench lie with the jaws furthest apart can it, the pivot pin, enter 35 or leave the recess, while in all other positions of the jaws the pin acts as the pivot of the parts, as set forth.

2. In combination in an adjustable wrench, two main parts, one hollow and 40 having a curved and roughened part forming one jaw of the wrench and the other solid and having a bent part with roughened edge forming the other jaw of the wrench, a pivot pin riveted to the two walls of and ex- 45 tending across the interior of the hollow part of the wrench and on that part inside the wrench provided with a flat portion, said solid part of the wrench extending through the hollow part, and having recesses in one 50 of its edges any one of which may only engage or leave the pin when that part of the pin of smallest diameter comes opposite the entrance of the recess, as set forth.

In testimony whereof I have signed my 55 name to this specification.

JOHN HENRY PICKARD.
